UNITED STATES PATENT OFFICE.

GEORGE T. COOLEY, OF JOPLIN, MISSOURI, ASSIGNOR OF ONE-HALF TO JAMES ATEL BRENT, OF SAN FRANCISCO, CALIFORNIA.

HEAD-MOTION FOR ORE-CONCENTRATORS

1,262,922.

Specification of Letters Patent. Patented Apr. 16, 1918.

Application filed November 10, 1914. Serial No. 871,306.

To all whom it may concern:

Be it known that I, GEORGE THOMPSON COOLEY, a citizen of the United States, residing at Joplin, in the county of Jasper and State of Missouri, have invented certain new and useful Improvements in Head-Motions for Ore-Concentrators, of which the following is a specification.

My invention relates to an improvement in head motions for ore concentrators, and the object is to provide apparatus especially adapted for operating tables on which material composed of the finest kind of grains is under treatment, it being desirable to employ apparatus which will impart a relatively short, quick motion, and especially rapid on the return stroke, while at the same time having such a degree of sensitiveness and flexibility that it will retain the very fine values upon the table, while the gangue is separated and eliminated therefrom, thereby saving a very high percentage of values which heretofore could not be saved either by vanners or slime tables.

With these objects in consideration, this invention consists of a reciprocating draw-bar, means for positively moving the latter in one direction, and a recoil for quick return, in connection with a table or tables and yielding means forming a connection between the table and the head motion, which relieves the suddenness and severity of the stroke which would otherwise be imparted to the table.

The invention further consists in details which will be hereinafter more fully described and set forth in the claims.

In the accompanying drawings:

Figure 1 is a plan view with certain portions broken away, showing the head motion mounted on a framework and connected to the end of a table; and

Fig. 2 is a longitudinal vertical section through the same.

A represents a framework composed of uprights and sills of any suitable form. Upon the top of this frame, a cast-iron base-plate 1 is bolted as at 2, 2. Pillow-blocks 3, 3, are erected at opposite sides of the base-plate 1, and in this the rotary drive-shaft 4 is journaled, the latter being held in place by the usual cap-plates 5, 5, held down by bolts 6, 6, upon the pillow-blocks.

Two eccentrics 7 and 8, one within the other, are located centrally on the rotary drive-shaft 4, the inner eccentric 7 being keyed thereon, and the outer eccentric mounted upon the inner eccentric and held adjustably in place thereon by set-screws or other means 9, 9.

A toggle-joint, consisting of the long and short links 10 and 11 respectively and the lever 12, is actuated by means of these eccentrics, the lever 12 being held thereon by means of cap 13, the flanges of which are rigidly secured to the flanges of the lever by the several bolts 14, 14. The eccentrics impart the required stroke to the lever, and the length of this stroke in the present designed machine is capable of variation from one inch to nothing by simply loosening the set-screws 9, 9, and turning the fly-wheel 15, which is affixed to the shaft, and which carries with it the inner eccentric 7, and holding the outer eccentric 8 until they are actually adjusted to the length of stroke required.

The reciprocating frame or yoke 16 conveniently encircles the toggle mechanism, and is reciprocated thereby. A tail-pin 17 slidably mounted in a hole in the post 18 on the base-plate 1, forms a guide and support at the rear end, and the draw-bar 19 sliding through a hole in the post 20 guides and supports it at the forward end. The long links 10, 10 of the toggle extend from trunnions 21 at the rear of the yoke or frame to trunnions 22 at the lower end of the lever 12, whereas the shorter links 11, 11, extend from trunnions 23, 23 on the abutment 24 to the trunnions 25 on the lever 12; so that with the rotation of the shaft 4, the lever 12 is not only reciprocated endwise but also a regulating motion is imparted to it, due to the location of the trunnions 22 and 25 in different horizontal planes and the difference in length of the toggle-links 10 and 11.

The bolt 19 is rigidly connected with the yoke or frame 16 by a nut 26, and the forward end of this bolt is rigidly secured to a bolster 27 by means of nuts 28 and 29 screwed thereon on opposite sides of the bolster, washers 30 and 31 being placed between the nuts and the bolster so that the bolster and screw are held rigidly together. A recoil compression spring 32 is sleeved

upon the bolt 19 and is held compressed between the washer 30 at the one end and the cup 33 on the cross-head 34. The tension of this spring is nicely regulated by means of screws 35, 35, which turn in threaded holes in the sides of the post 20. The heads of these bolts have round pins 36, 36, which turn in holes in the cross-head to hold the cross-head in place. By turning these screws 35, 35 to the left, the tension of the spring 32 is of course increased, and by turning them to the right, the tension is correspondingly decreased.

It is my intention to operate a battery of concentrator tables with my head motion. While the number may vary, I have shown four only, indicated by the numerals 37, 37. It is for this reason that I employ the bolster 27.

Especial attention is directed to the manner in which these tables are connected with the bolster. It is necessary, for the work this table is designed to accomplish, that it should have unusual flexibility and sensitiveness in the matter of imparting a stroke of the head motion to the table, as otherwise values which could be saved will necessarily be lost, and this is a meritorious feature of my invention and contributes largely to the successful treatment of the very fine material which constitutes a large percentage of the ore being dressed upon my table. This means of connection between head motion and table comprises bolts 38, 38, the springs 39, 39 concealed partly in the holes 40 bored into the bolster, and the tail-nuts 41, which are capable of being turned to regulate the tension of the springs 39, 39, while the machine is in operation. By means of these relatively small springs 39, 39, the suddenness and severity of the return stroke upon the table or tables—which necessarily must be rapid—is relieved, and the first shock or strain comes upon the springs 39, 39, which is then imparted to the tables through nuts 41, 41, and the bolts 38, 38. In this manner, the tables are relieved of the shock of the rapid return motion, which otherwise would be perfectly unyielding, but which through the medium of these springs 39, 39, is eased and softened and sensitive to the requirements of the work.

The drive-shaft 4 travels from five hundred to six hundred revolutions per minute. The parts are ordinarily adjusted to impart a quarter-inch stroke, as this keeps the fine stuff active and alive, without throwing it from the table. By the lever construction of the toggle, much less power is required than otherwise to drive the tables, and as the forward stroke is relatively slow, and then accelerated, the return stroke is relatively swift, so that the table is jerked back from under the load, as it were, whereas the load is carried with it in its forward stroke,

thus imparting an intermittent or step by step forward or progressive movement to the material on the table.

I claim:—

1. In a head motion for concentrators, the combination of a base-plate, a reciprocating frame or yoke, a rotary shaft, a toggle-joint actuated by the shaft comprising links and lever, said links extending from points on the lever in different horizontal planes to the yoke or frame and to a fixed abutment.

2. In a head motion for concentrators, the combination of a base-plate, a reciprocating frame or yoke, a rotary shaft, a toggle-joint actuated by the shaft comprising links and lever, said links of different lengths and extending from the lever at different points thereon to the frame or yoke and to a fixed abutment on the base-plate.

3. In a head motion for concentrators, the combination of a base-plate, a reciprocating frame or yoke, a rotary shaft, a toggle-joint actuated by the shaft comprising links and lever, said links extending from points on the lever in different horizontal planes to the yoke or frame and to a fixed abutment, the toggle links extending from the lever to the yoke or frame being of greater length than the links extending from the lever to the abutment.

4. In a head motion for concentrators, the combination with a suitable base-plate, a spring-actuated reciprocating frame or yoke, means for moving the frame or yoke positively in one direction while the spring moves it in the opposite direction, a bolster carried by the frame or yoke, and compressible means carried by the bolster, said compressible means consisting of rods extending slidably through the bolster, and adapted to be connected with the concentrator, springs on the rods, and means for regulating the tension of the springs.

5. In a head motion for concentrators, the combination with a suitable base-plate, a spring-actuated reciprocating frame or yoke, means for moving the frame or yoke positively in one direction while the spring moves it in the opposite direction, a bolster carried by the frame, compressible means carried by the bolster, said compressible means consisting of rods extending slidably through the bolster, and adapted to be connected with the concentrator, springs on the rods and means for adjusting the tension of said compressible means.

6. In a head motion for concentrators, a reciprocating frame or yoke, means for imparting a positive motion thereto in one direction, and a spring for moving it in the opposite direction, a bolster carried by the frame or yoke, and compressible means of less tension than the spring carried by the bolster or yoke for connection with the thing to be reciprocated, said compressible

means consisting of rods extending slidably through the bolster, and adapted to be connected with the concentrator, springs on the rods, and means for regulating the tension of the springs.

7. In head motions for concentrators, the combination with a suitable base-plate, of a reciprocating frame or yoke, a bolster, compressible means carried by the bolster, said compressible means consisting of rods extending slidably through the bolster, and adapted to be connected with the concentrator, springs on the rods, and means for regulating the tension of the springs, means for forcing the frame or yoke in one direction, and a spring for returning it in the other direction.
8. In a head motion for concentrators, the

combination with a base-plate, a reciprocating frame or yoke, means for driving the latter positively in one direction, and a spring for actuating it in the opposite direction, a cross-head with which one end of the spring engages, a bolster with which the other end of the spring engages, and bolts screwed into a part of the base plate with their heads rotatably connected with the cross-head, whereby, when they are turned, the tension of the spring is varied and tables yieldably connected with the bolster.

In testimony whereof I affix my signature in the presence of two witnesses.
